UNITED STATES PATENT OFFICE.

JOHN T. FANNING, OF MINNEAPOLIS, MINNESOTA.

STEAM-BOILER.

SPECIFICATION forming part of Letters Patent No. 635,923, dated October 31, 1899.

Application filed December 9, 1898. Serial No. 698,695. (No model.)

To all whom it may concern:

Be it known that I, JOHN T. FANNING, a citizen of the United States, residing at the city of Minneapolis, in the county of Hennepin and 5 State of Minnesota, have invented a new and useful Improvement in Steam-Boilers, of which the following is a specification.

My invention relates to that class of steam-generators containing an internal fire-box and 10 having fire-tubes leading therefrom, and has for its object an improved circulation of water within the boiler past the fire-box and fire-tubes.

The invention consists generally in the combination, with a fire-box boiler provided with 15 an annular generating-chamber and a water-distribution chamber connected with the base of the generating-chamber, of a water-gathering chamber surrounding the central parts 20 of the heights of the tubes and circulation-pipes connecting said gathering-chamber with said distribution-chamber.

The invention consists, further, in inclined annular disks arranged upon the outer surfaces of the fire-tubes for the purpose of deflecting the tube-enveloping current of steam 25 away from the tubes and giving to the water circulation past the tubes a spirally-upward movement, crossing the tubes, and thus adding 30 to the generating efficiency of the tubes.

The invention consists, further, in the constructions and combinations hereinafter described, and particularly pointed out in the claims.

35 In the accompanying drawings, forming part of this specification, Figure 1 is a vertical section through the centers of two of several units of the boiler. Fig. 2 is a horizontal section through four units of the boiler, in part 40 above the fire-box on line $x-x$ and in part below the grate on line $y-y$ of Fig. 1. Fig. 3 is a horizontal section through a boiler made up as a complete unit, but otherwise similar to the units shown in Figs. 1 and 2. Fig. 4 45 is a perspective view of one of the disks D shown on the fire-tubes in Fig. 1.

In a fire-box boiler, Fig. 1, as usually constructed, having its fire-box J surrounded by an annular water-space h , the fire-box wall 50 is subject to the intense direct heat of the fire, and steam is formed more rapidly in the annular space surrounding this fire-box wall

than in any other part of the boiler except near portions of the crown-sheet. The steam formed in the annular space h must escape in 55 an upward direction toward the steam-chamber i at the top of the boiler, and the rising steam tends to carry upward with itself the water of the annular space h , and this upward movement tends to prevent a downward 60 return flow of water in the same space to replace the water converted into steam.

In my improved boiler I construct an annular water-distribution chamber A beneath the annular chamber and preferably below 65 the level of the grate k , and connect this distribution-chamber A with the base of the annular space h , so as to supply the space h uniformly with water from below as rapidly as water may be required for conversion into 70 steam. This arrangement permits a free upward circulation of water and steam in the space h , surrounding the fire-box J. I form the distribution-chamber A, Figs. 1, 2, and 3, preferably by extending the annular space 75 around the fire-box downward below the level of the grate until it has capacity to distribute the water uniformly to the annular space h opposite to the fire, or by otherwise connecting the distribution-chamber A with the base 80 of the water-space h , so as to supply the latter with a full circulation of water from below the level of the grate. The distribution-chamber A is supplied with water from the gathering-chamber above by exterior pipes 85 or means other than flow downward through the annular water-space h , which surrounds the fire-box J.

In a fire-box vertical boiler, Fig. 1, the heating-surfaces in all parts of the boiler that are 90 generating steam are influencing an upward flow of steam and water adjacent to those surfaces. There is thus a tendency to an accumulation of water at the top of the boiler, and the return circulation to the base of the 95 boiler has heretofore been retarded by the upward flow of both steam and water. My improvement includes a water-gathering chamber c , combined with circulation-pipes B' , B^2 , and B , Figs. 1, 2, and 3, adapted to 100 return water freely from the water-gathering chamber in the boiler to the distribution-chamber A below the boiler, from whence it, with the feed-water, is distributed as circula-

tion may require into the base of the annular generation-chamber h , from whence it circulates upward along the heating-surfaces as the generation of steam may demand. The 5 return-water-circulation pipes B, Fig. 3, and B', B², and B, Figs. 1 and 2, are preferably attached to the outside of the exterior boiler-shell and project into the water-gathering chamber above and below the fire-box J. 10 They are one or more in number and are proportioned so as to give an adequate circulation of water and are supplied with nipples, elbows, bends, and unions for ready connections and to meet expansions and contractions with varying temperatures of the metals 15 of boilers and pipes.

In a compound boiler, Figs. 1 and 2, two or 20 more units may be grouped about one large combined mud-drum, steam-drum, and return-pipe B², which drum may be connected with each boiler unit and be a common return-pipe for the several units. In the latter case the base a of the large return-pipe B² is adapted to serve as a common mud-drum for 25 the several boiler units having circulation downward through it, and the top i^2 of the same enlarged return-pipe B² is adapted to serve as a common steam-drum and water-separator. In my improved boiler I place a 30 cylindrical thin diaphragm C and flange f to form an annular water-gathering space c adjacent to a portion of the inner surface of the upper part of the boiler-shell. This annular water-space c , which is open at the top for the 35 free flow of water from the water-space I in the upper part of the boiler, facilitates the flow of the uppermost portion of the water in the space I to the tops of the circulation-pipes B', B², and B, Figs. 1 and 2. A metallic deflection-ring f , Fig. 1, is placed just below the 40 lower edge of the diaphragm to obstruct in part a free flow of water out from or into the lower edge of the annular space c , surrounding the diaphragm C. The diaphragm C is 45 preferably constructed of a plate of thin metal and supported upon the ring f , forming the base of the chamber c .

In boilers having vertical fire-tubes $z z$, Figs. 1, 3, and 4, the tubes are in a considerable 50 part of their lengths exposed to the contact of flame and are in consequence efficient generators of steam, and the lower portions of the fire-tubes give the most rapid generation. In such cases the steam generated near 55 the bases of the tubes tends to follow upward and along and envelop the tubes, thus preventing free contact of water with the exteriors of the tubes and reducing their efficiencies and durability. In my improved boiler 60 I remedy this defect by placing upon the fire-tubes z the annular inclined disks D D, Figs. 1 and 4. The disks D are intended to deflect the tube-enveloping current of steam away from the tubes and to give to the water-circulation past the tubes a spirally-upward movement crossing the tubes, and thus add to 65 the generating efficiency of the tubes. The

stop-valves in the branch pipes B' B of the compound boiler, Figs. 1 and 2, give facility to cut off any one of the boiler units, so that 70 it will be out of common use or can be fired and worked independently as a complete boiler, and in like manner two or more units may be cut off or may be worked independently. When all the valves in the several 75 branch pipes are open, the several similar boiler units work together as one complete whole having a complete water-circulating system.

The gathering-chambers c , Figs. 1, 2, and 80 3, when combined with the pipes B' B² B, Figs. 1, 2, and 3, distribution-chambers A, Figs. 1, 2, and 3, and disks D, Figs. 1 and 4, produce a new and improved circulation in fire-box vertical boilers eliminating opposing currents 85 within the spaces h and I, Fig. 1. The improved circulation produced is a circuit of the water starting from the feed and distribution-chamber A, Fig. 1, upward through the annular space h , surrounding the fire-box, 90 then continuing spirally upward among the fire-tubes, deflected by the disks D to the top of the water-space I, then gathering in the annular space c , adjacent to the exterior upper shell of the boiler, then backward through 95 the return-pipes B', B², and B to the distribution-chamber A, thus completing and then continuously repeating the rounds of the unevaporated water and successively supplying 100 under the best conditions a new volume of water to the generating-surfaces.

What I claim, and desire to secure by Letters Patent, is—

1. In a fire-box vertical boiler having a generating-chamber, h , and fire-tubes, $z z$, the 105 plate C, with flange f , concentric with and attached to the exterior boiler-shell, forming a water-gathering chamber, c , in the upper part of the water-space, I, in combination with the circulating-pipes, B', B², B, the water-distribution chamber A, and deflectors, D, D, when arranged relatively to the water-space, I, and to the steam-generating space, h , and tubes, $z z$, as specified so as to cause a water circulation substantially as and for the purposes 115 described.

2. In a steam-generating apparatus comprising two or more vertical generators with internal fire-boxes inclosed by generating-chambers and having fire-tubes, a cylinder 120 B², serving for a steam-drum, a mud-drum and a circulating-pipe common to said generators, in combination with the pipes, B', B, connecting said generators with said cylinder and with the water-gathering chambers and 125 the distributing-chambers of said generators, when arranged substantially as and for the purposes described.

3. The combination, in a compound vertical boiler, with a series of boiler units, of a 130 separate cylinder serving for a steam-drum, a mud-drum, and a circulator for all the units of the boiler, connecting-pipes B, B' arranged between said cylinder and each of the boiler

units, and suitable stop-valves between said cylinder and said boiler units for the purpose set forth.

4. The combination, in a compound boiler, of a cylinder serving for a steam-drum, a mud-drum and circulator, a series of independent boilers, pipes connecting each of said boilers with said cylinder, and valves arranged in said pipes by means of which any one or more

of said boilers may be cut off from said cylinder, for the purpose set forth.

In witness whereof I have hereunto set my hand this 5th day of December, 1898.

JOHN T. FANNING.

In presence of—

A. C. PAUL,
M. C. NOONAN.
